OUTDOOR INCINERATOR

Phillip G. Larue, Bay City, Mich., assignor to Calcinator Corporation, Bay City, Mich.

Filed Nov. 16, 1970, Ser. No. 26,007

Term of patent 14 years

Int. Cl. D23—99

U.S. Cl. D23—85

FIG. 1

FIG. 2

FIG. 4

FIG. 3

FIG. 5

FIG. 1 is a front elevational view of an outdoor incinerator showing my new design;

FIG. 2 is a side elevational view thereof;

FIG. 3 is an opposite side elevational view thereof;

FIG. 4 is a rear elevational view thereof; and

FIG. 5 is a top plan view thereof.

I claim:

The ornamental design for an outdoor incinerator, substantially as shown.
